UNITED STATES PATENT OFFICE

173,279

TILE

Norman L. Martin, Lake Quivira, Kans., assignor
to Locke Stove Company, Kansas City, Mo., a
corporation of Missouri

Application November 12, 1953, Serial No. 27,556

Term of patent 14 years

(Cl. D18—2)

To all whom it may concern:

Be it known that I, Normal L. Martin, a citizen of the United States, residing at Lake Quivira, in the county of Johnson and State of Kansas, have invented a new, original, and ornamental Design for Tile, of which the following is a specification, reference being had to the accompanying drawings, forming part hereof.

In the drawings:

Fig. 1 is a front perspective view of a tile, showing my new design.

Fig. 2 is a rear perspective view.

Fig. 3 is an end elevational view.

Fig. 4 is a bottom view thereof.

I claim:

The ornamental design for a tile, as shown.
